Primary Examiner — Barbara Fox*Assistant Examiner* — Lilyana Bekic(57) **CLAIM**

The ornamental design for an inhaler refill assembly, as shown and described.

DESCRIPTION

FIG. 1 is a front isometric view of an inhaler refill assembly, showing the new design;

FIG. 2 is a front elevational view thereof;

FIG. 3 is a rear elevational view thereof;

FIG. 4 is a right side elevational view thereof, the left side elevational view being a mirror image of the right side elevational view;

FIG. 5 is a top plan view thereof; and,

FIG. 6 is a bottom plan view thereof.

The broken lines in the drawings illustrate portions of the inhaler refill assembly that form no part of the claimed design.

1 Claim, 2 Drawing Sheets(56)
